United States Patent Office

Des. 204,911
Patented May 24, 1966

204,911

CAMERA GUNSTOCK

Neil D. Adams, 9985 Lochiel Lane, St. Louis County, Mo.

Filed July 12, 1965, Ser. No. 86,128

Term of patent 14 years

(Cl. D61—1)

FIG. 1

FIG. 2

FIG. 3

FIG. 1 is a side elevational view of the camera gunstock, showing my new design;

FIG. 2 is an elevational view of the opposite side thereof; and

FIG. 3 is a top plan view thereof.

I claim:

The ornamental design for a camera gunstock, as shown.
